CASSETTE TRANSPORT

Leon C. Sanderson, Culver City, and David R. Crouch,
Los Angeles, Calif., assignors to Ampex Corporation,
Redwood City, Calif.

Filed Oct. 16, 1970, Ser. No. 25,524

Term of patent 14 years

Int. Cl. D14—01

U.S. Cl. D26—14

The sole figure is a front, top and left side perspective view of a cassette transport, showing our new design, the right side and rear being mirror images of the left side and front, respectively, and the bottom being conventionally plain.

We claim:

The ornamental design for a cassette transport, substantially as shown and described.
